United States Patent Office

Des. 181,527
Patented Nov. 26, 1957

181,527

ORNAMENTAL NAME PLATE HOLDER

William G. Grayson, Opa Locka, Fla.

Application July 6, 1956, Serial No. 42,157

Term of patent 3½ years

(Cl. D1—7)

I claim:

The ornamental design for a name plate holder, as shown.
